UNITED STATES PATENT OFFICE.

GEORGE B. COWLES, OF NEW BRITAIN, CONNECTICUT.

MACHINE FOR SLOTTING AND DRIVING SPRINGS INTO LOCK-TUMBLERS.

SPECIFICATION forming part of Letters Patent No. 286,269, dated October 9, 1883.

Application filed June 12, 1883. (No model.)

To all whom it may concern:

Be it known that I, GEORGE B. COWLES, a citizen of the United States, residing at New Britain, in the county of Hartford and State 5 of Connecticut, have invented certain new and useful Improvements in Machines for Driving Springs into Lock-Tumblers, of which the following is a specification.

My invention relates to improvements in 10 machines for slotting lock-tumblers and for driving the springs therein when fed from a continuous wire.

In the accompanying drawings, Figure 1 is a plan view of my machine. Fig. 1^a is a plan 15 view of a lock-tumbler with spring attached and bent. Fig. 2 is a vertical section of my machine through the line *x x* of Fig. 1. Fig. 3 is a vertical section on line *y y* of Fig. 1. Fig. 4 is a partial vertical section, partly in 20 elevation, upon line *z z* of Fig. 1. Fig. 5 is a plan view of detached parts, and Fig. 6 is a reversed plan view of a portion of my machine.

My said machine, in many of its parts and 25 in its general mode of operation, is substantially like the machine for driving springs into lock bolts and tumblers for which I have recently made application for Letters Patent of the United States.

30 This application is designed to cover only such features as are not embodied in the machine described in the prior application, and the combination thereof with other parts.

A designates the cam-shaft, bearing the several cams, of which *a* is the cam for driving the feeding mechanism B, said feeding mechanism being the same as has heretofore been used upon machines for feeding wire a given length at a time. I propose to take flat wire 35 in continuous lengths and pass it through this feeding mechanism B, then through the stationary member *b* of the cutting-off or shearing mechanism. The other member of the shearing mechanism consists of the plate *c*, 40 mounted upon the end of the shear-lever *C*, which is actuated by the cam *d* upon the cam-shaft A, said cam being partially shown in the sectional view, Fig. 3, while the rest of its 45 contour is indicated by the broken lines in said figure. From this shear mechanism the

wire passes under the driver *e*, said driver being provided with a slot or groove upon its under face, on that side which is toward the shearing device, while it has a flat under surface upon that part which comes over the 55 edge of the tumbler in the act of driving the spring. This driver *e* is mounted upon the end of the lever *D*, which is actuated by the cam *f*, the shape of which is fully shown by the sectional view, Fig. 3.

By the side of the driver is an intermittently-revolving head, *E*, the same being mounted upon a circular bed or table, *F*, and caused to revolve intermittently by means of the lever *G*, pawl *g*, pawl-carrier *h*, and ratchet-wheel *H*, substantially as in my aforesaid application, excepting that this lever, pawl, and ratchet-wheel are located upon the under side of the machine, instead of on the top. The lever *G* is operated in a direction to drive the pawl 70 forward by means of the cam *k*, while it is moved in the reverse direction by means of the spring *l*. This lever, pawl, and ratchet move the head intermittently one-eighth of a revolution at a time.

Upon the cam-shaft A is cam *m*, which acts upon a lever, *K*, to move it in one direction, while the spring *n* moves said lever in the opposite direction. The front end of this lever *K* is shown in Figs. 4 and 5, and it is turned upward 75 and made narrow enough to fill any one of the slots *o* in the head *E*, and is driven into one of said slots at the end of each intermittent movement of the head, so as to lock the head firmly in place. The upper surface of the upward extension of this lever *K*, which enters these slots, is of such height as to have its end flush with the top of the intermittently-rotating head *E*, and thereby it closes said slot and forms the anvil or bed for supporting the tumblers while the spring-wire is being driven edgewise in the tumbler.

The circular bed or table *F*, upon which the head *E* is mounted, is slotted upon the rear side in order to make room for the saw *p*. 95 This saw is mounted upon a suitable shaft or arbor carrying the driving-pulley *q*, which shaft and pulley are mounted upon a sliding carriage or frame, *L*. This carriage is acted upon by means of the cam *r* to drive it forward, 100

while it is pulled backward by means of the pin *s*, acting upon the rear part of the yoke *t*, as shown most clearly in Fig. 2.

In order to adapt the head to receive tumblers of varying sizes and forms, I provide said head with short pins or posts *u*, upon which the tumbler is placed, said pins entering the hole *v*, Fig. 1^A, and guiding that end of the tumbler.

10 I arrange upon the top of the head *E* two star-plates, *M* and *N*, the same being secured to the head *E* by the slot-and-screw connection, so that they may be partially rotated to different positions on their axis, and held in 15 the position in which they are adjusted by means of said screws. The star-plates *M* and *N* constitute the gages for governing the position of the tumblers. One corner of the tumbler will rest against one edge of the arms of 20 the plate *M*, while the arms of the plate *N* have downwardly-projecting pins near their ends, (the positions of which are indicated by broken circles in Figs. 1 and 5,) for gaging the position of the opposite corner of the tumblers. 25 These star-plates can be adjusted so as to bring the part of the tumbler which is to be slotted directly over the slots in the head *E*. The guard-plate *w* is placed over a portion of the head *E* at a sufficient height above 30 said head to allow the tumblers to pass under it. This plate is for the purpose of holding the tumblers down during the sawing and spring-driving operations.

P designates a curved lever, whose outer 35 end has a downwardly-extending pin or post which stands near the edge of the head *E*, as shown in Figs. 1 and 5. This lever is given a lateral movement by means of the cam *a'*.

The operation of my machine is as follows: 40 After adjusting the gages *M* and *N* so as to hold the tumbler in proper position on the head *E*, as one tumbler is represented in Fig. 5, the operator fills the front side of the head with tumblers, and the head, under the action 45 of the ratchet and pawl, moves around in the direction indicated by the dart in Fig. 1. At the end of each intermittent movement the cam *r* drives the saw *p* forward to saw the slot in the tumbler, and the saw is returned by 50 means of the crank-pin *s* and the yoke *t*. At the next intermittent movement of the head the next tumbler is sawed in like manner, and so on; but for convenience of description I will follow only one tumbler through the machine. 55 At the end of the second intermittent movement, and after being sawed, the tumbler is stopped under the driver *e*. At this point (after the machine has been started) the spring-wire will be fed into the machine through the

cutting-off mechanism, through the slot in the 60 under face of the driver *e*, and directly over the slotted portion of the tumbler. The cam *f* then acts to drive the spring edgewise into the slot in the tumbler. The wire springs edgewise between the tumbler and the shear 65 mechanism sufficiently to allow this driving action to take place. The cam *d* then acts to cut off the wire. At the next intermittent movement of the tumbler the feeding mechanism causes a length of wire sufficient for another spring to project from the shear mechanism again, and as the tumbler, with the spring driven into it, passes the outwardly-projecting pin on the end of the curved lever *P* the spring is partially bent around the end 70 of the tumbler, and the head *E* stops with the tumbler a little past the end of the lever, as shown in Fig. 5. The cam *a'* then acts to force this curved end and lever inward a little, and give a still farther bend to the tumbler-spring, and leaves it substantially in the 75 position represented in Fig. 1^A. As soon as the tumbler comes to the front of the machine the operator removes it and substitutes another tumbler therefor, and the operation is repeated so long as may be desired. 80

I claim as my invention—

1. The combination of the intermittently-revolving head, the saw mounted upon a reciprocating carriage, mechanism for feeding 90 the spring-wire, for driving the springs, for cutting off the wire, and suitable operating mechanism, substantially as described, and for the purpose specified.

2. The combination of the intermittently-revolving head, provided with suitable means for holding the tumblers thereon, mechanism for sawing the tumblers thus held, and mechanism for driving the springs into the slotted tumblers, substantially as described, and for 100 the purpose specified.

3. The combination of the intermittently-revolving and slotted head, mechanism for sawing slots in the tumblers, the spring-driving mechanism, the lever *K*, having its end 105 fitted to fill the slots in the head and to act as an anvil for the driving mechanism, and suitable operating mechanism, substantially as described, and for the purpose specified.

4. The combination of the head *E*, bearing pins *u*, and the adjustable gage-plates *M* and *N*, substantially as described, and for the purpose specified.

GEORGE B. COWLES.
